(57) **CLAIM**

The ornamental design for a tire, as shown and described.

DESCRIPTION

FIG. 1 is a side perspective view of a tire showing our new design;

FIG. 2 is a front elevational view thereof;

FIG. 3 is an enlarged fragmentary view thereof; and,

FIG. 4 is a side elevational view of the left side thereof, it being understood that the right side is the same.

In the drawings, the broken lines depict environmental subject matter only and form no part of the claimed design.
